CHEST

Orrin J. Mitchell, Le Roy, N. Y., assignor to Union
Steel Chest Corporation, Le Roy, N. Y., a corporation of New York

Application July 10, 1950, Serial No. 11,050

Term of patent 14 years

(Cl. D87—5)

To all whom it may concern:

Be it known that I, Orrin J. Mitchell, a citizen of the United States, residing at Le Roy, in the county of Genesee, and State of New York, have invented a new, original, and ornamental Design for Chests, of which the following is a specification, reference being had to the accompanying drawing, forming part thereof.

In the drawing:

Fig. 1 is a perspective view of a chest, showing my new design;

Fig. 2 is a longitudinal sectional view on line 2—2 of Fig. 1;

Fig. 3 is a cross sectional view on line 3—3 of Fig. 1; and

Fig. 4 is a bottom plan view.

I claim:

The ornamental design for a chest, as shown.
ORRIN J. MITCHELL.
